UNITED STATES PATENT OFFICE.

SAMUEL TRUSTON, OF MASSILLON, OHIO.

NUT-LOCK.

No. 922,543.

Specification of Letters Patent.

Patented May 25, 1909.

Application filed March 15, 1909. Serial No. 483,414.

To all whom it may concern:

Be it known that I, SAMUEL TRUSTON, residing at Massillon, in the county of Stark and State of Ohio, a citizen of the United States, have invented or discovered certain new and useful Improvements in Nut-Locks, of which improvement the following is a specification.

The invention described herein relates to certain improvements in means for locking nuts as against a loosening movement on bolts, and consists generally in a key or wedge engaging both the nut and bolt and provided with a surface at an angle to its axis and having a cutting edge in such relation to such surface that a portion of the metal of the nut or bolt will be forced by such edge against the surface, thereby locking the wedge in position.

20 The invention is hereinafter more fully described and claimed.

In the accompanying drawing forming a part of this specification Figure 1 is a sectional elevation of a bolt and nut locked by my improved means; Fig. 2 is a transverse section through the nut and bolt; Figs. 3 and 4 are views similar to Figs. 1 and 2 showing the key or wedge in reverse position; Fig. 5 is a view similar to Fig. 1 illustrating a further modification of my improvement; Fig. 6 is a perspective view of the key or locking piece; and Fig. 7 is a plan view of a nut to which the lock has been applied showing the locking tongue.

35 In the practice of my invention the key or wedge 1 is preferably formed with a cutting ridge 2 along one side or edge and its opposite side or edge flat, as clearly shown in Figs. 2 and 4. The shank of the key or wedge is gradually increased in thickness from the point to its head, so that it will have a wedging action when driven as hereinafter stated to lock the nut. The head 3 is made to overhang one of the edges preferably the flat edge opposite the cutting ridge 2, as shown in Figs. 1, 3 and 6, but the head may overhang the cutting ridge 2, as shown in Fig. 5. A bearing or locking surface 4 is formed adjacent to the upper end 40 of the shank and at an angle to its axis and preferably immediately below the head 3. The overhanging part of the head is provided with a cutting edge 5 arranged in such position relative to the locking surface 4, that a tongue of metal 6 which is formed by the cutting edge from the top of the nut or

bolt, will be forced over against the locking surface and thereby securely fasten the key or wedge in position. It is preferred to form the locking surface and the cutting edge 5, 60 by cutting a groove 7 at the junction of the head and shank, said groove being at an acute angle to the axis of the shank.

In using my improved key it is forced in between the nut and bolt, so as to engage 65 both. Its introduction may be facilitated by forming grooves for its reception. It is preferred to form a groove 8 in the nut of such depth relative to the thickness of the wedge, that the longitudinal cutting ridge 2 will be 70 forced to a greater or less depth into the threads on the bolt. As shown in Figs. 3, 4 and 5 the groove for the introduction of the key or wedge may be formed in the bolt and the cutting ridge forced into the threads of 75 the nut. When driving the key down its cutting edge 5 will enter the nut or bolt and will force a tongue of metal 6 into the groove and over against the locking surface 4, and thereby lock the wedge as against being accidentally loosened. The cutting ridge 2 will not so greatly injure the threads as to prevent the nut or bolt being again used.

It is preferred that the overhanging portion of the head on which the cutting edge 5 85 is formed should be made narrower than the groove in the nut or bolt, so as to facilitate the bending of the tongue of metal against the locking surface. As will be readily understood, if the cutting edge should be made of a 90 width equal to or greater than the width of the groove, the edges of the tongue will have to be sheared or torn loose in order that the tongue may be bent in against the locking surface. Whereas by making the cutting 95 edge narrower than the groove, the metal as along the edges of the tongue will readily stretch and permit the inward movement of the tongue, as shown in Fig. 7.

I claim herein as my invention:

1. A lock for nuts, consisting of a shank portion constructed to engage the nut and bolt, having a locking surface adjacent to its upper end and provided with a cutting edge suitably arranged with reference to the locking surface that a tongue of metal formed by the cutting edge from one of the parts to be locked will be forced against the locking surface.

2. A lock for nuts consisting of a shank 110 portion constructed to engage the nut and bolt, and a head overhanging one edge of the

shank, said parts having a groove cut therein adjacent to their junction, the groove being at an acute angle to the axis of the shank, thereby forming a locking surface and a cutting edge.

3. A lock for nuts consisting of a shank portion constructed to engage the nut and bolt, and a head overhanging one edge of the shank, said parts having a groove cut therein adjacent to their junction, the groove being at an acute angle to the axis of the shank, thereby forming a locking surface and a cutting edge, said edge having a width less than the width of the shank.
- 10 4. A lock for nuts consisting of a tapering

shank portion having a cutting ridge along one edge and having a head overhanging the edge, the shank being provided with a locking surface at an angle to the axis of the shank and the head having a cutting edge 20 arranged to form a tongue on one of the parts to be locked and force the said tongue against the locking surface.

In testimony whereof, I have hereunto set my hand.

SAMUEL TRUSTON.
